UNITED STATES PATENT OFFICE.

JOSEPH L. MANLOVE, OF PARIS, ILLINOIS.

IMPROVEMENT IN AUTOMATIC GATES.

Specification forming part of Letters Patent No. 174,547, dated March 7, 1876; application filed November 16, 1875.

To all whom it may concern:

Be it known, that I, JOSEPH L. MANLOVE, of Paris, in the county of Edgar and State of Illinois, have invented a new and useful Improvement in Automatic Gates, of which the following is a specification:

This invention relates to that class of double gates through which vehicles pass, and which open and close automatically when the rods attached to them are acted upon by the passage of the wheels of such vehicles over them. The object of this invention is to provide means for facilitating the opening and closing of the gates. To attain this, my improvement consists of obliquely-slotted hinge-plates secured to the lower ends of the gate-posts, and hooked plates secured to the lower ends of the gate-frames nearest the posts, the hooks of the latter plates playing in the oblique slots of the former, so that when the rods which are attached to the hooks move the latter in the slots, (the upper ends of the frames turning on ordinary permanent hinges,) the gate will be overbalanced, and will open or close as the case may be.

In the annexed drawings, Figure 1 is a perspective view of my improved automatic gate. Fig. 2 shows the shape of my improved hinge-plates. Fig. 3 is a perspective view of the latches attached to the center block.

Into the upper ends of two ordinary gate-posts A and A' hooks a² are driven, while to the lower ends of the same obliquely-slotted hinge-plates a and a¹ are secured. These plates, the shape of which is clearly shown in Fig. 2, are preferably made of cast-iron, while the hooked plates C and C', (see Fig. 2,) which tightly clamp the lower ends of the frames B and B', are preferably made of wrought-iron. Into the upper ends of the gate-frames, nearest the posts, eyes or staples b are driven. When the frame B is hung in position on its post A, the hook c of plate C on said frame, descending through the slot in hinge-plate a on post A, is embraced by the hooked ends of the three rods D, E, and F. The rod D, the first to embrace hook c, and which is laid in the direction in which the gate opens, exceeds rods E and F considerably in length. Its outer end is pivoted to the crank-arm g, which is permanently secured to rock-shaft G.

This rock-shaft stretches across the drive parallel with the gate, and is held in position by staples g³, or may turn in bearings of suitable blocks. The rod E, occupying a central position on the hook c, traverses the ground parallel with, and immediately under, the gate, and terminating a short distance beyond the center block K, is pivoted with its hooked end to the short arm of lever L, which is fulcrumed at l, and forms a connecting-link between rods E and I, as clearly shown in Fig. 1. The arms of lever L are so proportioned that the throw of rod E will impart the required throw to rod I to move hook c' from one end of the slot in plate a' to the other. One end of rod I being pivoted to the long arm of lever L, its other hooked end encircles hook c' of the plate C' on frame B'. The rod F, which occupies the lowest position on hook c, and the length of which is about equal to half of that of rod D, is laid across the ground in an opposite direction to the latter. It is pivoted to the crank-arm h, which is permanently secured to rock-shaft H. The rock-shafts G and H have each two bows, g¹ and g² and h¹ h², respectively, standing at an angle of about ninety degrees to each other, as usual.

The gate is opened and closed in the following manner: When the bow h¹ of rock-shaft H is forced down by the wheel of a vehicle, the crank h, by turning, will set all the rods in motion. Thus, while rods F and D are pulled back, and rock-shaft G is made to turn in its bearings, depressing bow g¹ and raising bow g², the rod E pushes forward and, by turning lever L on its pivot, causes said lever to pull back rod I, so that, as both the hooks c and c' have their positions in the respective slots changed at one and the same time, while the upper hinges remain stationary, the frames B and B' are overbalanced and will swing open. The latches M secured to the stakes N, as in Fig. 1, and which are made of spring-steel, catch the lower and outer ends of the frames and hold them securely while the vehicle passes through the gate. As the wheel of the vehicle forces down the raised bow g² of rock-shaft G, the rods D and F are pulled forward, and rock-shaft H turned in its bearings h³, while rod

E, being pulled back, will cause the lever L to push forward the rod I, so that the hooks e and e' are simultaneously returned to their former positions in the slots; the frames, thus overbalanced again, will be lifted off the latches M and swung back to the center block K, where they will be held in position by latches O attached to said block. These latches are secured to the pin P, (see Fig. 3,) and work in the hollow center block K, both ends of pin P having bearings in that block. The latches are held apart by means of another block which is placed inside the block K.

A box, buried in the ground, may be used to cover the rods between the posts, and will at the same time act as a brace for the gate-posts. The rod D is carried over an anti-friction roller r on the lower tang of the staple R, which is driven into the stake, thus reducing the friction and facilitating the movements of the rods.

The rock-shafts G and H, intersecting the drive, should be of a length sufficient to allow the bows thereof to be so far apart that when the front wheel at one side of a vehicle de-

presses and passes over one bow there will be no danger of the raised bow coming in contact with the other wheels of such vehicle.

What I claim as my invention, and desire to secure by Letters Patent, is—

The combination, substantially as before set forth, with a pair of gates, each of which is hung to its post at one end by an ordinary hinge, and at the other end by a hinge composed of an obliquely-slotted plate and a hook or pintle, of the arched or bowed rock-shafts G H, the cranks g h thereon, the rods D F for connecting the cranks to the pintle of the adjusting hinge of one of the gates, and the rods E I and intermediate lever L for connecting the pintles of the adjustable hinges of the two gates.

In testimony whereof I have signed my name to this specification in the presence of two subscribing witnesses.

J. L. MANLOVE.
